UNITED STATES PATENT OFFICE

ROBERT C. HAM, OF WEST HAVEN, CONNECTICUT, ASSIGNOR TO R. C. HAM & COMPANY, INC., OF NEW HAVEN, CONNECTICUT, A CORPORATION OF CONNECTICUT

DESIGN FOR A FLOWER HOLDER

Application filed February 11, 1930. Serial No. 34,488. Term of patent 14 years.

To all whom it may concern:

Be it known that I, ROBERT C. HAM, a citizen of the United States, residing in West Haven, in the county of New Haven and State of Connecticut, have invented a new, original, and ornamental Design for a Flower Holder, of which the following is a specification when taken in connection with the accompanying drawing.

Fig. 1 is a front elevation of a flower holder according to my invention; and

Fig. 2 is a sectional view taken along line 2—2 of Fig. 1.

The spherical member supported by the shaft is provided with a mirrored surface.

I claim:

The ornamental design for a flower holder substantially as shown and described.

ROBERT C. HAM.
